BENJAMIN BIGGS, OF SEATTLE, WASHINGTON.

FORM FOR CONCRETE SILO CONSTRUCTION.

1,301,364.

Specification of Letters Patent. Patented Apr. 22, 1919.

Application filed January 6, 1919. Serial No. 269,780.

To all whom it may concern:

Be it known that I, BENJAMIN BIGGS, a citizen of the United States, and resident of the city of Seattle, county of King, 5 and State of Washington, have invented certain new and useful Improvements in Forms for Concrete Silo Construction, of which the following is a specification.

My invention relates to forms designed 10 for use in molding circular concrete walls, such for instance as concrete silos.

The object of my invention is to provide sectional forms which may be conveniently used for this purpose and which may be 15 adjusted so as to be used in making silos of considerable size in its diameter.

My invention consists of certain peculiar constructions and combinations of parts, which will be herein described and then defined by the claims.

The accompanying drawings show the manner of constructing my forms.

Figure 1 shows, in horizontal section, one of the segments used for forming the outer 25 surface of the silos.

Fig. 2 shows, in horizontal section, one of the segments used in forming the inner surface of the silos.

Fig. 3 is an inside face view of one of the 30 segments, showing a portion of one of the ribs broken away.

Fig. 4 shows, in horizontal section, a section designed for forming the outer surface of the silo.

Fig. 5 is a fragmentary view showing the 35 face of one of the sections which contains the molding surface against which the concrete is poured.

One of the objects of my present invention 40 is to provide a mold form which may be adjusted so as to be used in the construction of silos, and other circular walls, which vary considerably in diameter. To this end I construct a form which is in segments 45 and add to or remove segments, as may be necessary, to get the proper circumferential dimension for the silo of the size desired, and at the same time provide means whereby the molding surface, which is next 50 to the concrete, may be adjusted in curvature to correspond with the curvature of the size of silo being made.

In Fig. 4 is shown, in cross section, the 55 vertical staves 1 and the sheet metal plate 2, which forms the molding surface or that which is in contact with the concrete when

poured. These staves 1 may be of such vertical length as desired. I prefer to make these of comparatively short length and to employ the molds by pouring a certain 60 vertical section of the wall and then raising the molds for pouring the next vertical section.

The sheet metal plate 2 should be secured to these staves so as to permit free bending 65 with the limits which would be employed for any particular segment. I have shown these as being provided with slots 20, through which pass the shanks of screws 21, the latter screwing into the staves 1, which 70 staves are made of wood. This permits a certain amount of slipping of the sheet metal over the surface of the staves, which are toward the ends of the segment.

I also employ two or more stiffening bars 75 3 which are secured to the opposite sides of the staves 1. These bars are made of flat bar iron, of such a size as to provide a certain measure of stiffness and yet not so heavy but that they may be bent within 80 relatively small limits.

These bars are shown as secured to the staves by means of screws 30, which pass through holes in the bars. These bars are also provided with holes for the reception 85 of bolts 4. I prefer to locate these bolts so that they go within the outline of the staves, and to recess these staves to accommodate the heads of the bolts. I also provide a nut 40, or other means, whereby the 90 bolt may be fixedly secured to the bar 3.

Along with the above parts I provide two stiffening ribs 5 for each segment. These ribs would preferably be made of wood and means would be provided whereby the meeting edges of adjacent segments would be secured to each other. The bolts 4 pass through, or are otherwise secured to the ribs 5. These bolts are secured in proper position with relation to the ribs by the 100 use of additional nuts, 41 and 42, which engage opposite edged surfaces of the ribs.

The portion of the segments represented by the staves 1, the sheet metal plate 2, and the iron bars 3 possesses a sufficient amount 105 of flexibility, so that its curvature may be varied and thus be made to fit the curved outline of silos of different diameters. The manner of securing this part of the segment to the ribs 5 provides a convenient 110 means for securing this variation in curvature.

Referring to Fig. 2, which shows a segment designed for shaping a portion of the inner surface of the wall, the curved edge of the rib 5 being the edge which is next to the staves 1, is made of a curvature which would be substantially that of the smallest size of silo which it might be desired to mold by the use of this device.

In molding such a silo, the bar 3 would be bent so as to fit closely against the edge surface of the rib throughout its length. If, however, it be desired to use the mold to form a silo of larger diameter, the end portions of the sections of staves which form this segment, would be disposed and held outwardly enough to conform to the curvature of the desired silo. This may easily be done by adjusting the bolts 4 through the means of the two nuts 41 and 42. I also contemplate the employment of wedges, or spacing blocks, 6, which would be inserted between the metal bar 3 and the edge of the rib 5.

The mold segments which would be used for forming the outer surface of the wall would be constructed along similar lines. In this case the sheet metal plate 2 would be bent into concave shape, and the curved edge of the rib 50 would also be concaved. In forming these outer segments, the curvature of the edge of the rib would be made substantially that which conforms to the curvature of the silo of a larger diameter, which it might be desired to make, and the mold would be adjusted for making silos of smaller diameter by forcing outward the side edges of the series of staves which compose this segment.

I have found that by this scheme I can use the same mold for constructing silos varying in size throughout substantially the entire limit of diameters ordinarily used. Of course, where a large silo is being made, additional segments will have to be inserted over what would be required for a smaller sized silo. It may be desirable to have one or more segments of a lesser width than the majority, in order to more accurately get the correct curvature, and in order to mold a silo of the exact size desired. This, however, may be easily done and any mechanic would know how to do this.

I prefer to carry the surfacing sheet 2 somewhat beyond the edges of the staves, as is shown at 22, and to overlap this edge of one segment over the corresponding edge of

the adjacent segment, thus making a continuous molding surface.

What I claim as my invention is:

1. A form for molding silos and like circular concrete walls, comprising a series of vertical segments adapted to be assembled to form the circular outline, said segments having transversely extending ribs and longitudinally extending staves, bars connecting the staves of each section and adapted to bend to conform to the curvature of walls of different diameters, and means for adjustably securing said bars to the ribs. 60

2. A form for molding silos and like circular concrete walls comprising segmental ribs extending about the form, vertical staves, surfacing sheets secured to said staves, and means for supporting the staves from the ribs to permit supporting them at 75 variable distances from the edge faces of the ribs, to thereby vary the radius of curvature. 70

3. A form for molding silos and like circular concrete walls comprising segmental ribs, extending about the form, vertical 80 staves, surfacing sheets secured to said staves, bolts securing said staves to the ribs at intervals, and spacing members adapted to be inserted to variably space the staves away from the ribs to thereby vary the radius of curvature of the wall molding surface. 85

4. A form for molding silos and like circular concrete walls comprising segmental ribs extending about the form, vertical 90 staves, surfacing sheets secured to said staves, segment bands extending across and securing together the staves for each segment rib, and bolts securing said bands to the ribs and permitting variable adjustment of the 95 radius of curvature of the wall molding surface.

5. A form for molding circular concrete walls comprising a series of segments adapted when assembled to extend about the circle, 100 each segment having horizontal ribs, vertical staves and a surfacing plate secured to the staves and extending beyond the staves to overlap on the adjacent segments, means separate from the ribs for connecting the staves of each segment, and means for supporting the staves from the ribs permitting local adjustment toward and from the ribs to secure variation in the radius of curvature. 105

Signed at Seattle, Washington, this 30th day of December, 1918. 110

BENJAMIN BIGGS.
